UNITED STATES PATENT OFFICE.

FRANZ A. MOENCH, OF MILWAUKEE, WISCONSIN.

ELECTROPNEUMATIC UNIT VALVE FOR PIPE ORGANS.

Application filed June 26, 1922. Serial No. 571,097.

To all whom it may concern:

Be it known that I, FRANZ A. MOENCH, a citizen of the United States, and resident of Milwaukee, in the county of Milwaukee and State of Wisconsin, have invented certain new and useful Improvements in Electro-pneumatic Unit Valves for Pipe Organs; and I do hereby declare that the following is a full, clear, and exact description thereof.

10 The invention relates to electro-pneumatic unit valves for pipe organs.

It comprises a wind chest, in which a plurality of the valve mechanisms are installed. Each of the valve mechanisms comprises a 15 valve, the position of which is controlled by air pressure in the wind chest and electro-magnetic means for determining the action of the air pressure on the valve. The valve and electro-magnetic means are made in one 20 complete unit.

The primary object of the invention is the provision of a valve unit which may be inserted into the wind chest from below, thus leaving the pipes untouched and not in any 25 way interfering with the musical condition of the pipe organ. Whereas, heretofore, the removal of dust and foreign matter from valves has necessitated, in some constructions, the removal of pipes, this is not necessary in the novel device. The removal and 30 reinsertion of a pipe are inconvenient and oftentimes adversely affect the musical character of the instrument.

The object of the invention is the provision of a construction which can be readily tested to determine its operativeness, and which may be conveniently shipped, all parts being united in a single unitary structure.

An important object of the invention is 35 the provision of a valve mechanism which may be conveniently removed and replaced. In the event of derangement in the magnet or valve structure, the entire unit may be readily and promptly removed. The operation 40 does not require a skilled mechanic and may be accomplished even without the use of tools.

Another unit valve may be conveniently 45 inserted. If no reserve unit valve is at hand, a blind unit to cover the pipe and bottom hole in the chest may be used until the defective unit is replaced.

An important feature of the invention is 50 the provision of an adjuster. As atmospheric conditions and variations in temperature may alter the distance at which the

valve is disposed above the bottom board, means are provided for taking up the distance between the opening in the top board and the valve. Thus swelling and shrinkage 60 in the chest are instantly taken up by the adjuster so that the valve action is at all times reliable.

With the above and other objects in view, which will appear as the description proceeds, my invention resides in the novel construction, combination and arrangement of parts, substantially as hereinafter described and more particularly defined by the appended claims, it being understood that such 70 changes in the precise embodiment of the herein disclosed invention may be made as come within the scope of the claims.

In the accompanying drawing, I have illustrated one complete example of the physical embodiment of the present invention constructed according to the best mode I have so far devised for the practical application of the principles thereof, and in which:

Figure 1 is a sectional view through a 80 wind chest, showing one of the units in side elevation and another in vertical, central section, the section being substantially on the line 1—1 of Figure 2.

Figure 2 is a section on the line 2—2 of Figure 1.

Wind chest 10 is provided with a top board 11 and a bottom board 12. The top board has a plurality of openings 13 adapted to receive the lower tapered ends of pipes 90 14. Bottom board 12 is provided with a plurality of openings 15. Each of the openings 15 registers with an opening 13. A closure 16 has a cylindrical portion 17 received in opening 15 and is provided with a flange 18 95 having a gasket 19 thereon adapted to contact with the surface of bottom board 12 adjacent opening 15, in such wise that escape of air is not possible.

Closure 16 is apertured to receive a hollow cylinder 20, the bottom of which is threaded for the reception of plug 21 having a vent 22 therein. Cylinder 20 has an opening 23 in the side thereof registering with a duct 24 in plug 16, the duct communicating with pipe 25 rigid with plug 16. The top of cylinder 20 is threaded for engagement with cap 26, which is rigid with termini 27 of electro-magnet 28. Cap 26 is provided with a pair of apertures 29.

A metallic valve 30, having a felt face 31, rests upon the top of plug 21 and pre-

vents air under pressure in chest 10 from escaping through vent 22. Actuation of electro-magnet 28, which is accomplished by the organist, in a manner well-known and common in the art, lifts valve 30 and thus puts pipe 25 in communication with the atmosphere through a vent 22. The upper end of pipe 25 is rigid with cylindrical box 32 and the pipe communicates with a chamber 33 therein, the top of which is covered by a diaphragm 34.

Installed in the bottom of the box are cushions 35 adapted to noiselessly withstand the impact of rigid valve 36, which is secured to the diaphragm and has soft fibre discs 37 and 38 thereon. Post 39 is rigid with valve 36 and is received in the end of helical spring 40, the tension of the spring being regulated by screw 41 received in an opening 20 in box 32.

When valve 30 is in the position shown in Figure 1, the air pressure in chamber 33 is the same as that of the air in wind chest 10. On the operation of electro-magnet 28 and the lifting of valve 30, the pressure of the air in chamber 33 is lowered to that of the atmosphere. This results in a dropping of valve 33, the air in wind chest 10 acting on diaphragm 34.

30 A spacer 42 is rigid with closure 16 and box 32. Thus valve 36, pipe 25, electromagnet 28, and closure 16 are united in one unit. Contacts 43 extend through closure 16 and are provided with laterally directed superficial portions 44, against which retainers 45-45' are adapted to abut. The retainers are rotatable on screws 46 and 46' and may be moved into such position as to permit the insertion of closure 16, whereupon they may be rotated to the position shown in Figure 2. The manner in which the circuit is closed by the organist is well-known to those skilled in the art.

45 As is apparent, valve 36 and associated structure may be placed in position or removed without necessitating any tampering with pipes 14. Thus the musical character of the device is in nowise varied when the valve units are repaired and cleaned. A 50 valve unit may be removed and dusted separately from all other parts of the organ, and the association of parts in an integral unit is such as to facilitate shipment. Obviously, the removal of the entire unit valve may be accomplished even by one unskilled in the art. Thus a valve may be readily removed and cleaned without necessitating the presence of a skilled workman.

60 In the event of derangement of a valve, if no reserve unit is at hand, a blind unit may be used to cover the pipe and bottom hole in the chest until the defective unit is repaired.

65 Extreme atmospheric conditions and temperatures may cause a swelling or shrinkage

of chest 10. This would result in varying the distance between valve 36 and top board 11 and might cause an angling of valve 36 with respect to the top board. An adjuster is therefore provided. It consists of annuli 70 47-47' having openings therein in registry with opening 13. The annuli have a flexible cover 48 adapted to be expanded and contracted and a helical spring 49 terminates in minor recesses in the annuli and maintains them in spaced relation, the limit of separation being determined by cover 48.

The adjuster is not necessary to the operation of the device, but where it is used, the annulus 47' is secured in box 32 by a plurality of spacers 50. The adjuster is, therefore, a part of the valve unit and is inserted with the valve and cooperating parts through opening 15 in bottom board 12. The annulus 47 is provided with a gasket 51, preventing 85 the escape of air between the annulus 47 and top board 11, the helical spring 49 maintaining the gasket 51 tightly in position.

80 Spacers 50 maintain a definite spaced relation between box 32 and annulus 47' so that valve 36 is maintained in a predetermined and definite position irrespective of variations of temperature and atmospheric conditions.

90 The operation of valve 36 on the actuation of electro-magnet has been described. Obviously, when the magnetic action ceases, valve 31 is permitted to return to position shown in Figure 1, and the pressure of air of wind chest 10 is sufficient to move air 100 through openings 29 and 23', duct 24 and pipe 25, bringing the pressure of the air in chamber 33 up to that of air in the wind chest and cause valve 36 to rise to the position illustrated in Figure 1.

105 I claim:

1. The combination with an organ wind chest having a bottom board provided with an opening and a top board provided with an opening, of a valve, a box, a diaphragm 110 covering said box and secured to said valve, a closure for the opening in said bottom board, a pipe communicating with said box at one end and at another end with said closure, said closure having a duct therein communicating with said pipe, said closure having openings communicating with said wind chest, a vent communicating with the atmosphere, a second valve normally closing said vent, and electro-magnetic means for elevating said second valve to cover said openings, whereby said vent is put into communication with said duct, said pipe, and said box.

115 2. The combination of a valve, a box, a diaphragm closing said box and secured to said valve, a spring in said box for maintaining said valve in outer position, a pipe in communication with said box, a closure rigid with the lower end of said pipe, a duct in 120

130

- said closure communicating with said pipe, said closure having an opening and a vent therein, a second valve in said closure normally closing said vent, and electro-magnetic means operable to lift said valve to close said opening and put said vent in communication with said duct.
3. The combination of a valve, a box having a chamber therein, a diaphragm secured to said valve and said box, a spring in said box maintaining said valve normally in outer position, and a cushion in said box adapted to receive the impact of said valve.
4. The combination of a top board having an opening therein, a valve, and an automatically adjustable member interposed between said valve and said opening for taking up variations in distance between said valve and said opening.
5. The combination with an organ wind chest having a bottom wall provided with an opening, a top board provided with an opening, of a closure for said opening in said bottom board, a valve, a self-adjusting member having an opening in communication with said opening in said top board and an opening normally closed by said valve, and electro-magnetically controlled means structurally united with said electro-magnetically controlled means and said valve for determining the position of said valve.

6. The combination of a top board having an opening therein, a box, a valve, a diaphragm secured to said valve and covering said box, a member secured to said box and having an opening therein normally covered by said valve, and means for conveying air through said opening in said member to said opening in said top board, said means being extensible to take up variations in distance between said valve and said top board.

7. In a pneumatically controlled device, the combination of a stationary board having an opening therethrough, a pair of members having openings therethrough, means tending normally to separate said members and a flexible means secured to said members and permitting limited relative movement between said members, one of said members being held in contact with said stationary board with its aperture in registry with the aperture of said stationary board, said flexible member preventing the escape of air between said members or between said stationary board and the member contacting therewith.

In testimony that I claim the foregoing I have hereunto set my hand at Milwaukee, in the county of Milwaukee and State of Wisconsin.

FRANZ A. MOENCH.
